PROCESS FOR TREATING HYDROCARBON OILS

Filed June 15, 1926

UNITED STATES PATENT OFFICE

JOHN C. BLACK, OF LOS ANGELES, CALIFORNIA, ASSIGNOR TO GASOLINE PRODUCTS COMPANY, INC., OF WILMINGTON, DELAWARE, A CORPORATION OF DELAWARE

PROCESS FOR TREATING HYDROCARBON OILS

Application filed June 15, 1926. Serial No. 116,217.

This process relates to an improvement in the art of cracking hydrocarbons to produce lower boiling point hydrocarbons from those of higher boiling point.

5 This invention also relates to a process of cracking petroleum oils wherein a body of oil is heated to a cracking temperature and maintained at an active cracking temperature over a prolonged period of time and introducing 10 into the body of oil at the termination of its cracking period a cooler stream of oil to check the cracking reaction of the main stream of oil and simultaneously increase the heat of the injected oil to a cracking tem-

15 perature whereby an increased yield of gasoline is obtained, an increased yield of recycle stock, better operative conditions and decreased production of carbonaceous material are secured.

20 In my Patent 1,456,419, there is described a process for the production of lower boiling point hydrocarbons from those of higher boiling point which comprises preheating the oil in a heating coil to the point of active decom-

25 position. The oil thus heated is then subjected to a further heat treatment where it is maintained at the temperature attained in the preheating coil and the endothermic heat of the cracking reaction supplied. In passing

30 through the second heating or cracking coil the hydrocarbons are subjected to the cracking temperature and maintained for a sufficient length of time to obtain the desired cracking effects. In this coil the endother-

35 mic heat of the cracking reaction is supplied. The stream of oil is kept under sufficient pressure to prevent substantial vaporization.

The hydrocarbons passing from the cracking or reaction coils are then passed either to a 40 carbon settling chamber or reaction chamber for further decomposition and carbon deposition.

In the present invention the above mentioned principle of operation is employed but 45 I split the advancing stream of oil at a chosen point in the series of coils and conduct one of the streams which I denominate the by-pass stream into the lower or final passes of the reaction coil. This introduction of the 50 by-pass stream into the reaction coils is made

possible for the reason that there is a difference in pressure between the point of the by-pass connection and the point of re-entrance into the reaction coils which is represented by the pressure drop due to friction between 55 the two points. By this procedure several advantages are to be gained which assist in the operative control of the process and also an increased yield of gasoline or low boiling point hydrocarbons may result as will appear 60 as I describe the process in more detail.

If I operated my process with the by-pass connection closed and passed through the system of coils a given quantity of hydrocarbons, I would obtain a certain percentage of decomposed hydrocarbons at the temperature employed, and I would find that the final passes of the reaction coil would gradually foul with carbon and the apparatus would have to be shut down to be cleaned. I have 70 found that if I by-pass a portion of the stream of hydrocarbons and inject the by-passed portion into the final passes of the reaction coil that I will obtain a greater yield of decomposed hydrocarbons in that portion of the 75 stream passing through the main reaction coil than if the whole stream passed through. I also have found that the fouling of the tubes is very materially lessened by the injection of the by-pass stream and furthermore, 80 I have found that the hydrocarbons of the by-pass stream are also partially decomposed by the admixture with the hotter hydrocarbons of the main stream, and also by the heating effect derived from the furnace 85 while passing through the final passes of the reaction coil.

The above may be understood by the consideration of the following. While I do not limit myself to the theory here advanced I 90 believe the same to be a probable explanation of the phenomena observed. It is apparent that in operating, according to my former method and without the use of the by-pass, the oil reaching the final passes will have been 95 highly cracked with a large formation of light oils which do not crack easily. The oil stream also contains heavier bodies formed probably as a result of the cracking reaction. The practical oil man says that 100

the oil becomes "dirty". The oil stream and the fire are so manipulated as to maintain the temperature of the stream at the chosen cracking temperature. Any transfer of heat 5 that results then goes to carbonize the heavy bodies depositing a dense carbon on the walls of the tubes. The tubes then become overheated and the result is that as more oil advances the carbonization at the film between 10 the oil and tube becomes more and more severe.

Another result is that this high temperature cracking at the surface of the hot tube causes the formation of a large amount of 15 gas which builds up a high vapor pressure, which may, if carried to excess, exceed the operating pressure and interferes with the operation of the process.

The introduction of a partially heated un-cracked oil into the final passes avoids this 20 difficulty, since the latter oil tends to absorb heat by having its sensible heat raised by the cracked oil entering the final passes, thereby lowering the temperature of the cracked oil. 25 The partially cooled stream then absorbs heat from the combustion gases and the tube wall surface, to have its temperature raised to substantially the desired cracking point, and the uncracked oil further absorbs heat due to its 30 absorption of heat of reaction. There is therefore a large transfer of heat from the combustion gases to the oil passing through the final passes of the coil in the present invention. The tube is kept from overheating 35 and the excessive surface carbonization, as above described, is prevented.

By the present invention I am enabled to obtain a combined yield of cracked or decomposed hydrocarbons equal to or better than 40 the yield obtained by a single stream operation, and at the same time get better operative conditions as regards fouling and time on stream.

Furthermore, by the injection of the by-pass stream the carbonaceous material deposited in the reaction coil is of a softer composition and is more readily removed in the blowing down operation and the heaters can be put back on stream with less loss of time. 45 I prefer to use multiple connections on the by-pass header so that the temperature of the by-pass stream can be varied by manipulation of the valves, whereby the main stream may be tapped at several points in the heating coil as the heating progresses. The temperature and quantity of the by-pass stream should be so chosen that the temperature of the admixed streams may be such that decomposition of the by-passed stream may be 50 partially accomplished and to obtain a temperature of the mixture such that the decomposition is checked or reduced in the main stream of hydrocarbons, and the carbon of decomposition is minimized and deposited from a cooler liquid suspension. This, as

stated previously, will be of a softer nature and more easily purged from the system. The purging of the system of carbonaceous material is accomplished by the injection of water into the coils, as described in my Patent 1,456,419.

The hydrocarbons emerging from the reaction coil may be passed to a carbon depositing chamber or reaction chamber where the carbonaceous material may be deposited, and further decomposition of the hydrocarbons may be effected if the reaction, through one cause or another, is not complete. On the other hand, the hydrocarbons may be passed through a heat exchanger wherein the heat is 75 reduced to a point suitable for subsequent fractionation upon release of pressure and discharge into a suitable fractionating apparatus.

The operation of the heat exchanger may 80 be varied at will by the regulation of the by-pass on the incoming raw stock so that the temperature of the hydrocarbons upon release of pressure will permit those fractions to vaporize that are desired and the residue 85 to separate out.

In the drawing, I show a single heat exchanger connected to the direct discharge line and also to the carbon precipitating chamber using valves properly located to cut in 90 or out either branch. Although in practice I prefer to use one system or the other whereby the valves may be eliminated. Whether I use the reaction chamber or go direct to the heat exchanger and fractionating apparatus largely depends upon the nature of the 95 hydrocarbons. If I am working with a heavy oil I would prefer to by-pass the reaction chamber or cut it off entirely whereas with a lighter oil it may be found advantageous to use the reaction chamber if it is 100 found that a better conversion of the hydrocarbons is obtained or if the carbonaceous material is more effectively handled by its use.

In this process I use such a pressure imposed by mechanical means upon the hydrocarbons during the decomposition stage of the process as to overcome the vapor pressure of the mixture of hydrocarbons. This pressure will vary with each particular grade of hydrocarbons and to the amount of decomposition to which the hydrocarbons have been subjected. This pressure should be predetermined for each individual stock under 115 treatment for if substantial vaporization is permitted carbonaceous deposits will soon form and curtail the operation of the process.

As an illustration of the process I may 120 by-pass twenty percent of the stream through the by-pass connection at a temperature of say 625° F. and combine it in the last pass or passes of the reaction coil, wherein it meets a volume four times as great at a temperature of say 890° F., the temperature 130

of the mixture is then 837° F., and in passing through the final passes of the coil it may attain a temperature of 850° F. The result is this: the main stream (which in this case is 80% of the total stream entering the system) would attain 80 per cent of the velocity of the total stream in this case, and consequently would remain in its reaction coil up to the point of injection, 20/80 or 25 per cent longer time and thereby increase its decomposition above what it would have attained if it had passed through at the rate of the total stream. The 20% by-passed stream is practically uncracked at the point of entrance into the reaction coil but upon admixture with the main stream it is instantaneously heated from 625° to 837° which increase in temperature is sufficient to partially decompose it, and it will also be further decomposed in passing through the final passes of the reaction coil where it will attain a temperature of 850° F. or more. The lowering of the temperature of the main stream from 890° to 837° F. will check the decomposition of the main stream with its resultant carbon decomposition and the lower passes of the coil will be materially freed from fouling. The prevention of fouling is also assisted by the fact that the hydrocarbons passing through the final passes of the reaction coil can absorb heat from the furnace without being heated above a good operative temperature, whereas if the hydrocarbons had entered the final passes of the reaction coil at 890° F. and passed out at the same temperature, practically no heat would be transferred to the hydrocarbons other than the endothermic heat of reaction, and as a result the steel of the tubes would become overheated with a tendency to burn out and carbon would rapidly form on the inside circumference of the tubes and in a short time would cause plugging of the tubes, necessitating shutting down to clean them out.

Instead of by-passing the preheated oil and introducing the same into the final passes to meet the advancing stream of cracked hydrocarbons, a cold uncracked oil may be introduced into the final passes of the cracking coil. By regulating the point of introduction of the oil in the cracking coil so as to increase the length of time and the heating effect which the cold oil receives analogous results may be obtained. In operating in this way care must be taken to regulate both the quantity of oil introduced and the point of introduction.

The invention will be better understood by reference to the drawing which shows schematically an embodiment of my invention.

Referring to the drawing, 1 represents a heating furnace and 2 represents the primary heating coil. 2' is a crossover between coils 2 and 4; 3 is a heating furnace and 4 is the secondary heating coil. 5 represents the final

passes of the secondary coil or series of coils and 6 represents a waste heat or economizer coil. 6' is a connection between coil 6 and coil 2 and also header 7. 7 is a header connected to the primary coil through connection 8 and valve 8', also connection 9 and valve 9'. It also connects to pipe 6' through pipe 54 and valve 54'. 10 is a connection from the header 7 to the heating coil 4, and 10' is a control valve in pipe 10. 11 is a valve in the pipe 28 and connects with economizer coil 6 and 11' is a valve in the cross connection between pipe 28 and the entrance to the series of coils 2 and 4. 12 connects the outlet of the coils 2 and 4 with the reaction chamber through pipe 13 and valve 13' and pipe 14 and valve 14'. In pipe 12 is a valve 12'. Pipe 12 connects with the heat exchanger 15. 16 is an outlet connection from heat exchanger 15 to the fractionating tower 17 and 16' is a pressure regulating and discharge valve in pipe 16. 18 is a connection for conducting the heavy ends and gas oil cut from the fractionating tower 17 to the cooler. 19 is a connection from the cooler to the gas oil tank and 19' is a valve thereon. 20 is a connection to the gas oil tank and connects with pump 21 through pipe 22 and valve 22'. 20 also connects with pump 23 through pipe 24 and valve 24'. 25 is a connection from pump 23 connecting with a spray connection 26 in the fractionating tower 17. 27 is a connection from pump 21 to the gas oil supply tank through connection 41, and 27' is a valve in pipe 27. 28 is a discharge connection from the pump 21 to the heat exchanger 15, and 28' is a valve in pipe 28. 29 is a by-pass connection around the heat exchanger 15 and connects into pipe 28. 29' is a valve in pipe 29; 30 is a pump connected to the heavy oil tank through connection 31 and valve 31', and to the gas oil tank through connection 32 and valve 32'. 33 is a discharge connection from pump 30 connecting with the economizer coil 6 and 33' is a valve in pipe 33.

The numeral 35 designates a vapor pipe connecting the fractionating tower 17 with the condenser 36, which in turn is connected with the light oil tank through connection 37 and look box 38. 39 is a gas vent connecting with the gas header 40. 41 is a connection between the supply tank and pumps 21 and 30. 41' is a valve in pipe 41 and 42 is a connection from the bottom of the fractionating tower 17 connecting with the residue tank, and 42' is a valve in pipe 42. 43, 44, 45, 46, 58 are pyrometer connections on the various coils, 47 is a blow down connection and 47' is a blow down valve on pipe 47. 48 is a blow down connection from the reaction chamber and 48' is the blow down valve on pipe 48. 49 and 50 are pressure gauges on the pumps 21 and 30 respectively. 51 is a terminal pressure gauge to indicate the pressure at the point of pressure release and dis-

charge. 52 is a connection to the recycle oil tank and 52' is a valve thereon. 53 is a connection from pipe 33 connecting to the final passes 5 of coil 4 and 53' is a valve in pipe 53. 54 is a connection between header 7 and pipe 6', and 54' is a valve in pipe 54. 55 is a valved connection between pipe 6' and the coil 2. 56 is a valve on header 7 between the inlet of coil 6 and pipe 54. 57 is a connection from the water tank to the pump 21 and valve 57' is in pipe 57.

I will now describe the operation of my process. It will be noted that I can inject various grades of oil into the final passes of the secondary heating coil, such as fresh gas oil from the gas oil supply tank, gas oil from the re-run gas oil tank and heavy oil from the heavy oil tank or combination of these various grades of oil, whichever method is used is optional with the operator and will depend upon the class of hydrocarbons being handled.

Let us assume first that we are handling gas oil in pump 21 and heavy oil in pump 30; pump 21 takes suction on the re-run gas oil tank and discharges it through the heat exchanger 15, if too much cooling effect on the outgoing oil from the heat exchanger is produced by passing all the oil from pump 21 through the heat exchanger, then the valve 29' in by-pass 29 is so regulated that the proper temperature is obtained in the oil entering the fractionating tower 17, that is by proper regulation of valve 29' I can bypass any quantity of oil I desire around the heat exchanger and thereby regulate the temperature of the outgoing oil, the valve 28' is also regulated in conjunction with valve 29'. The oil now passing through 28 enters the coil 2 in furnace 1 (valve 11 being closed and 11' being open and valve 55 being closed) and is heated to a temperature as determined by pyrometer 43 equal to approximately the temperature chosen for the cracking reaction. (This temperature depends upon the character of the oil—a higher temperature for the light oils and a lower temperature for the heavier oils.) It then passes over to coil 4 through crossover 2' and is supplied with heat from the furnace 3 in sufficient quantities to approximately maintain its temperature uniform throughout its passage through coil 4, that is at the temperature chosen for the reaction and which it attained in coil 2 as stated above. That is, the temperature indicated by pyrometer 44 is equal to approximately that at 43. The oil now enters the final passes of coil 4 which is shown as a single layer of tubes and marked 5 on the drawing. However, the final passes of coil 4 may consist of any number of layers of tubes but for convenience is shown as one layer. Coincident with the gas oil entering the final passes of coil 4 there is introduced into the stream a second supply

of oil which has been pumped from the heavy oil tank by pump 30 and discharged through pipe 33 to the economizer coil 6 located in the waste combustion gas spaces of furnaces 1 and 3, valve 33' being open and valve 53' closed and valve 54' and 10' being open.

The temperature of this second supply of oil is maintained at a lower temperature than the gas oil stream and is determined by pyrometer 45. The two commingled streams of oil now pass through the final passes 5 of coil 4 wherein the mixture of oils may function, in the above described manner. The mixture of oils now passes out of the heating coils (its temperature being determined by pyrometer 46) into pipe connection 12 which connects with the reaction chamber or it may go direct to the heat exchanger 15. If I elect to pass the oil through the reaction chamber I would close valve 12' and open valves 13' and 14', then pass the oil through the heat exchanger where its temperature is reduced and regulated as explained above. It then discharges through pipe 16 and pressure reducing and discharge valve 16' to the fractionating tower 17 where the various hydrocarbons are separated, such as a residue that may be drawn off thru pipe 42 and valve 42' and run to the tank marked "Residue oil". Also a heavy condensate may be separated and drawn off through pipe connection 18 passed through the cooler and through pipe 19 and valve 19' to the re-run gas oil tank to be re-run. There is a by-pass connection 52 and valve 52' to permit of withdrawing a portion of the re-run gas oil into the tank marked "Recycle oil" for subsequent recirculation wherein it is subjected to a higher cracking temperature.

A portion of the re-run gas oil cut is recirculated through the fractionating tower by means of pump 23 taking suction through pipes 20, 24 and valve 24' and discharging through pipe 25 to the spray connection 26 in the fractionating tower 17. There is also a vapor cut taken from the tower 17 which is conducted by pipe 35 to the condenser 36 where the vapor is condensed, the condensate being conducted to the light oil tank through pipe 37 and look box 38, any uncondensed gases passing out of the look box 38 through the pipe 39 to the gas header 40.

The above description will give a clear idea of the operation of the process wherein a heavy oil and a gas oil are processed. The operation when gas oil alone is used is very similar to the above operation as for instance, pump 21 may handle re-run gas oil as in the previous operation, and pump 30 may handle oil from the fresh gas oil supply tank through pipe 41 and valve 41', and discharge it through pipe 33 and 33' in similar manner to the method when handling heavy oil. Also pump 21 can simultaneously handle oil from the re-run gas oil tank and from the gas

oil supply tank, while pump 30 is handling oil from the heavy oil tank.

It will also be observed that pump 21 can handle re-run gas oil, taking the make-up oil from the gas oil supply tank to keep the system fully charged without the assistance of pump 30. In this method of operation pump 21 only is used as a charging pump, taking its make-up oil from the gas oil supply tank through pipe 41 and connection 27 and valve 27', and at the same time takes suction from the re-run gas oil tank through pipe 20 and 22 and valve 22' and discharges it through pipe 28 and exchanger 15 and (or) 15 by-pass 29 thence to the economizer coil 6 through valve 11 with valve 11' closed and discharges it through the valved connection 55 into coil 2, thence through crossover connection 2' into coil 4 and to the final passes 20 of coil 4. As the oil enters the final passes 5 the oil meets an advancing stream of oil which has been by-passed from the original stream of oil entering the apparatus and may be by-passed through any of the valves 25 54', 8', 9', 56 into the header 7 and through valve 10' and connection 10 into the final passes 5 of coil 4 where it meets the stream advancing through coil 4. The admixed streams now pass through the final passes 5 30 of coil 4 and discharge through pipe 12 to the reaction chamber and heat exchanger 15 or direct to the heat exchanger, as previously described, thence to the pressure reducing and discharge valve 16' in pipe 16 35 and discharge into the fractionating tower where the oil is fractionated as previously described.

If I wish to inject relatively cold oil into the final passes 5, I would open valve 56 connecting the inlet pipe of the heater to header 7 and have the valves 54', 8', 9' closed. From header 7 the oil may be discharged through valve 10' and connection 10 into the final passes 5 as previously described. If I wish 40 to by-pass heated oil to the final passes 5, I can introduce oil heated in a graduated degree by having valve 56 closed and opening valve 54' whereby the temperature of the oil by-passed would have the temperature attained in the economizer coil 6, or if a higher temperature were desired, I would open valve 8' which is further advanced in the series of coils and obtain a by-passed portion of oil at a higher temperature than that obtained through valve 54'. Also in like manner I could obtain a still higher temperature in the by-passed portion of oil by tapping the coil at any point desired as the oil progressed through the heating coil. Such 45 a connection is shown at 9 and valve 9' and is shown as a single connection but is indicative of any number of by-pass connections and to show them would be a useless repetition. In this manner I am enabled to obtain 50 a wide range of temperatures in the by-

passed oil entering the final passes 5 to perform the functions described in the foregoing specification.

If heavy oil or re-run gas oil or fresh gas oil is circulated through the economizer coil 6, and the main stream passes directly to coil 2 and thence to coil 4, while part of the oil from coil 6 is mixed with the oil advancing through the final passes of coil 4 thereof, the following will actually take place.

The oil passing through the economizer coil is heated to a relatively lower temperature than the main stream and on mixing of the two oils the temperature of the oil heated in the economizer coil is raised to a cracking temperature and cools the advancing stream from coil 4. As described previously this permits of an advantageous transfer of heat through the walls of the tubes in the final passes 5 preventing the deposition of carbon, and yet permitting a sufficient heating of the mixed oils to crack the uncracked oil and regulate the temperature of the exiting stream from the final passes.

Other combinations of the charging oil may be made other than those above enumerated, as for instance, pump 30 could introduce fresh gas oil into the system through the economizer coil, thence through header 7 and connection 10 into the final passes 5, while pump 21 was handling re-run gas oil through the main heating and cracking system or pump 30 could introduce cold fresh gas oil direct into the final passes 5 through pipe 53 and valve 53' with valve 33' closed, and pump 21 handling re-run gas oil through the economizer coil 6 in series with coils 2 and 4, or pump 30 could handle re-run gas oil direct to the final passes 5 through connection 53, and pump 21 could handle fresh gas oil and re-run gas oil through the main heating and cracking coils. Pump 30 can also feed heavy oil from the heavy oil tank via valve 53', valve 33' being closed directly to the final passes of coil 5. Pump 21 can handle re-run gas oil or fresh gas oil, or mixtures thereof, for introduction via heat exchanger 15 directly to coil 2. The point of introduction of the oil into the final passes will depend upon the character of the oil employed in order to allow the oil to receive sufficient heating for a sufficient length of time and also to allow the mixed oils to be heated up to their required temperature.

If I inject heavy oil into the system by means of pump 30 and discharge it through coil 6 and by-pass header 7, valve 10' and connection 10 into the final passes 5 of coil 4, there meeting the main stream of cracked oil emerging from coil 4, it will be increased in temperature to a cracking degree, the temperature of the heavy oil stream being so regulated that its temperature will be below that of the main stream, and as the mixed stream heated to a cracking temperature of

the heavy oil passes through the final passes 5 it will be subjected to an increasing cracking temperature and also to a prolonged reaction time and will be able to absorb heat of reaction and the quantity of oil passing through the coil is so regulated that its final temperature emerging from the final passes 5 will not be substantially above the operating temperature of the main stream of oil

10 entering the final passes 5. In this manner I prevent in large measure the formation of carbonaceous material in the tubes, and accomplish a substantial cracking of the heavy oils which upon distillation will produce 15 products not in the original oil such as gasoline and an increased yield of intermediates, such as gas oil or recycle stock.

In a similar manner the injection of re-run gas oil or fresh gas oil through coil 6 20 into the final passes 5 will bring about the same results, or if these oils are by-passed from coil 2 through header 7, and injected into the final passes 5, the same result may be obtained as recited above. It can be readily 25 understood that combinations of heavy oil, re-run gas oil and fresh gas oil can be made by the proper operation of the apparatus to make variations of the mixture of stocks to yield the desired final products.

30 It can be seen that a very large number of combinations may be made with the two pumps and the two grades of gas oil and the heavy oil, all of which may be advantageous at times depending upon the stock used

35 and the method of introducing the various oils to the heating and cracking system. It will be noted that water may be introduced into the coils for purging them of carbonaceous material by pump 21 taking suction on

40 the water tank through pipe connection 57 and valve 57' with valve 22' closed. The water and steam and carbonaceous material, after passing through the coils is blown out to waste through the blow-off valve 48' and

45 or valve 47'. It is to be understood, however, that an auxiliary pump may be used for handling the water for the reason that pump 21 may be used for charging several units that would not require purging at the same

50 time, and a bad operative condition would be created if the same pump had to function as an oil charging pump and as a water purging pump at the same time. If an auxiliary water pump is used the water should

55 preferably be introduced at a point beyond valves 28' and 29' into pipe 28 or beyond valve 33' in pipe 33 or beyond valve 53' in pipe 53.

60 While I have explained my invention in connection with its application to the high pressure system disclosed in my Patent 1,456,419, I do not limit myself to this system or to pressures stated therein. This invention is applicable to any system where oil 65 passes through coils and is there heated to a

cracking temperature whether or not the cracking reaction is completed in the coils. It is applicable to any cracking system wherein a tendency towards deposition of carbon or the formation of carbonaceous materials occurs in the tubes. Its application to other systems, it is believed, will be obvious to those skilled in the art from the above disclosure.

75 I claim:

1. A process for cracking oil which comprises continuously flowing a stream of oil through an elongated continuously heated passageway and heating the oil to a cracking temperature during its flow therethrough, withdrawing from an intermediate point of said passageway a portion of the said stream of oil, and introducing the said withdrawn oil into said passageway at a point intermediate the said point of withdrawal and the outlet of said passageway.

80 2. A process for cracking oil which comprises continuously flowing a stream of oil through an elongated continuously heated passageway and heating the oil to a cracking temperature during its flow therethrough, withdrawing from an intermediate point of said passageway a portion of the said stream of oil, regulating the temperature of said withdrawn portion of oil, and introducing the said withdrawn oil into said passageway at a point intermediate the said point of withdrawal and the outlet of said passageway.

85 3. A process for cracking oil which comprises continuously flowing a stream of oil through an elongated continuously heated passageway and heating the oil to a cracking temperature during its flow therethrough, withdrawing from an intermediate point of said passageway a portion of the said stream of oil, introducing the said withdrawn oil into said passageway at a point intermediate the said point of withdrawal and the outlet of said passageway, and continuing the heating of the blended stream of oil during its further flow through said passageway.

90 4. A process for cracking oil which comprises continuously flowing a stream of oil through an elongated passageway heated throughout its length and heating the oil to the desired cracking temperature during its flow therethrough, withdrawing from an intermediate point of said passageway a portion of the said stream of oil, continuing the heating of the remaining stream to supply the endothermic heat of the cracking reaction and to obtain the desired cracking thereof, introducing the said withdrawn oil into the passageway at a point where the desired cracking of the said oil stream is substantially completed, and continuing the flow through said passageway of the blended stream of oil while continuing the heating to effect further cracking thereof.

5. A process for cracking oil which comprises continuously flowing a stream of oil throughout its length and heating the oil to the desired cracking temperature during its flow therethrough, withdrawing from an intermediate point of said passageway a portion of the said stream of oil, continuing the heating of the remaining stream to supply the endothermic heat of the cracking reaction and to obtain the desired cracking thereof, introducing the said withdrawn oil into the passageway at a point where the desired cracking of the said oil stream is substantially completed, regulating the temperature and volume of the withdrawn oil to obtain a temperature of the admixed oil formed on the introduction of the said withdrawn oil into the said passageway sufficient to crack the un-cracked oil in the admixture, and continuing the flow through said passageway of the blended stream of oil while continuing the heating to effect further cracking thereof.

6. A process for cracking oil which comprises continuously flowing a stream of oil through an elongated continuously heated passageway and heating the oil to a cracking temperature during its flow therethrough, withdrawing from an intermediate point of said passageway a portion of the said stream of oil, introducing the said withdrawn oil into said passageway at a point intermediate the said point of withdrawal and the outlet of said passageway, and maintaining the oil during its flow through said passageway under pressure sufficient to prevent substantial vaporization thereof.

7. A process for cracking oil which comprises continuously flowing a stream of oil through an elongated continuously heated passageway and heating the oil to a cracking temperature during its flow therethrough, withdrawing from an intermediate point of said passageway a portion of the said stream of oil, regulating the temperature of said withdrawn portion of oil, introducing the said withdrawn oil into said passageway at a point intermediate the said point of withdrawal and the outlet of said passageway, and maintaining the oil during its flow through said passageway under pressure sufficient to prevent substantial vaporization thereof.

8. A process for cracking oil which comprises continuously flowing a stream of oil through a coil mounted in a furnace, heating the oil during flow therethrough to a substantial cracking temperature, withdrawing a portion of the oil from said stream at an intermediate point of said coil, by-passing the withdrawn oil and introducing it into the stream of heated oil at a point intermediate the said point of withdrawal and the outlet of said coil and at a point where the said stream has attained a substantial cracking

temperature, and supplying additional heat to the oil during its further flow through said coil.

9. A process for cracking oil which comprises continuously flowing a stream of oil through a coil mounted in a furnace, heating the oil during flow therethrough to a substantial cracking temperature, withdrawing a portion of the oil from said stream at an intermediate point of said coil before said stream of oil has attained a cracking temperature, by-passing the withdrawn oil and introducing it into the stream of heated oil at a point intermediate the said point of withdrawal and the outlet of said coil, and at a point where the said stream has attained a substantial cracking temperature, and supplying additional heat to the oil during its further flow through said coil.

10. A process for cracking oil which comprises continuously flowing a stream of oil through a coil mounted in a furnace, heating the oil during flow therethrough to a substantial cracking temperature, withdrawing a portion of the oil from said stream at an intermediate point of said coil, by-passing the withdrawn oil and introducing it into the stream of heated oil at a point intermediate the said point of withdrawal and the outlet of said coil and at a point where the said stream has attained a substantial cracking temperature, regulating the temperature of said by-passed portion of oil to modify the temperature of the oil in the zone of introduction, and supplying additional heat to the oil during its further flow through said coil.

11. A process for cracking oil which comprises continuously flowing a stream of oil through a coil mounted in a furnace, heating the oil during flow therethrough to a substantial cracking temperature, withdrawing a portion of the oil from said stream at an intermediate point of said coil, by-passing the withdrawn oil and introducing it into the stream of heated oil at a point intermediate the said point of withdrawal and the outlet of said coil and at a point where the said stream has attained a substantial cracking temperature, regulating the temperature and volume of said by-passed portion of oil to modify the temperature of the oil in the zone of introduction, and supplying additional heat to the oil during its further flow through said coil.

12. A process for cracking oil which comprises continuously flowing a stream of oil through a coil mounted in a furnace, heating the oil during flow therethrough to a substantial cracking temperature, withdrawing a portion of the oil from said stream at an intermediate point of said coil, by-passing the withdrawn oil and introducing it into the stream of heated oil at a point intermediate the said point of withdrawal and the outlet of said coil and at a point where the said stream has attained a substantial cracking

let of said coil and at a point where the said stream has attained a substantial cracking temperature, regulating the temperature and volume of said by-passed portion of oil to 5 modify the temperature of the oil in the zone of introduction, supplying additional heat to the oil during its further flow through said coil, and maintaining a pressure on the oil during its flow through said coil sufficient to 10 prevent substantial vaporization of said oil.

13. A process for cracking oil which comprises heating a stream of oil flowing through a coil mounted in a furnace to a temperature sufficient to crack it and under pressure sufficient to prevent material vaporization, withdrawing a portion of the oil from an intermediate point of the coil before reaching its cracking temperature, by-passing the withdrawn oil and reintroducing it into the heated 20 stream of oil passing through the coil at a point subsequent to the point of withdrawal, continuing the flow of the stream through said coil and supplying additional heat thereto while maintaining the said stream under 25 said pressure.

14. A process for cracking oil which comprises heating a stream of oil flowing through a coil mounted in a furnace to a temperature sufficient to crack it and under pressure sufficient to prevent material vaporization, withdrawing a portion of the oil from an intermediate point of the coil, by-passing the withdrawn oil and reintroducing it into the heated stream of oil passing through the coil at a 30 point subsequent to the point of withdrawal and after the heated stream of oil has attained a cracking temperature, continuing the flow of the stream through said coil and supplying additional heat thereto while maintaining the said stream under said pressure.

15. A process for cracking oil which comprises heating a stream of oil flowing through a coil mounted in a furnace to a temperature sufficient to crack it and under pressure sufficient to prevent material vaporization, withdrawing a portion of the oil from an intermediate point of the coil before reaching its cracking temperature, by-passing the withdrawn oil and reintroducing it into the heated stream of oil passing through the coil at a point subsequent to the point of withdrawal, continuing the flow of the stream through said coil, supplying additional heat thereto while maintaining the said stream under said 50 pressure, and conducting the stream of oil to a fractionating device and fractionating the oil.

16. A process of cracking hydrocarbon oils comprising, heating oil under superatmospheric pressure while passing once through a continuous heating coil mounted in a furnace, continuing the supply of heat to the oil passing through the coil for a prolonged period of time to maintain it at a substantially constant cracking temperature, with-

drawing a portion of the stream of oil at an intermediate point in its passage through the coil, reintroducing said withdrawn portion into the heated stream of oil passing through the coil at a point in the path of flow of the oil through the coil subsequent to the said point of withdrawal, in quantities sufficient to lower the temperature of the mixed oil stream to check the cracking reaction of the heated portion of the main stream of oil, and continuing the flow of the blended oil stream through said coil while supplying additional heat thereto to effect further cracking thereof.

17. A process of treating oil comprising passing the oil through a coil mounted in a furnace and simultaneously heating the same to a temperature sufficiently high to crack the oil and under pressure sufficiently high to prevent material vaporization of the oil, withdrawing a portion of the oil from an intermediate point of the coil before it has been cracked, then introducing the cooler, withdrawn, uncracked oil at a point in the path of flow of the oil through the coil subsequent to the said point of withdrawal in quantities sufficient to check the cracking of the main stream of oil by reducing the temperature thereof, continuing the flow of the blended stream through said coil while supplying additional heat thereto to effect further cracking thereof while maintaining said pressure on the blended stream, releasing the pressure on said stream of oil and discharging it into a fractionating apparatus to fractionate the same.

In testimony whereof I affix my signature.

JOHN C. BLACK.
